UNITED STATES PATENT OFFICE.

GEORGE B. ROBBINS, OF HINSDALE, AND WILLIAM E. SHARP, OF CHICAGO, ILLINOIS.

STEEL UNDERFRAME FOR RAILWAY-CARS.

No. 926,897.

Specification of Letters Patent.

Patented July 6, 1909.

Application filed May 29, 1908. Serial No. 435,808.

To all whom it may concern:

Be it known that we, GEORGE B. ROBBINS and WILLIAM E. SHARP, both citizens of the United States, residing, respectively, at Hinsdale and Chicago, in the county of Cook and State of Illinois, have invented certain new and useful Improvements in Steel Underframes for Railway-Cars, of which the following is a specification.

10 This invention relates to, improvements in steel underframes for railway cars, and has for its main object to provide an improved construction in which the steel center-sills and draft-arms on opposite sides 15 of the body-bolster are securely joined through the latter, so as to form a continuous anchorage for the draft-gear running from end to end of the car to withstand both buffing and pulling strains.

20 In carrying out our invention we employ a body-bolster, preferably made continuous from side to side of the underframe, and connect the abutting ends of the draft-arms and center sills on the opposite sides thereof 25 through the agency of links passing through the body-bolster on opposite sides of the draft-arms and center-sills, said links being strongly secured at their ends to the draft-arms and center-sills. In the particular 30 embodiment of the invention herein shown, these links are secured to the draft-arms and center-sills through the agency of keys passed transversely through the draft-arms and links on one side of the bolster and 35 through the center-sills and links on the opposite side of the bolster, in such a manner as to transmit through said links both draft and buffing strains in either direction. We also preferably employ in addition to the 40 parts specified, hollow filler castings interposed between and riveted to the two draft-arms and the two center-sills and abutting against the body-bolster, which castings, in the construction herein shown, are trans- 45 versely apertured for the passage of the said keys.

The invention will be readily understood when considered in connection with the accompanying drawings, showing a practical 50 mechanical embodiment thereof, in which—

Figure 1 is a top plan view of the complete structure. Fig. 2 is a longitudinal vertical section on the line 2—2 of Fig. 1. Fig. 3 is an end view of Fig. 1.

Referring to the drawings, 5 indicates a 55 body-bolster herein shown as continuous from side to side of the car.

6 designates each of a pair of center-sills shown as of outwardly facing channel form, the ends of which abut against the side of 60 the body-bolster either directly as shown, or through the intervention of one or more filler castings, as shown in our pending application on underframes for railway cars, Serial No. 409,458, filed January 6, 1908. 65 7 designates each of a pair of steel draft-arms, also shown as of outwardly facing channel form, the inner ends of which either directly or indirectly abut against the outer side of the bolster 5.

8 designates each of a pair of links that are passed through the body-bolster 5 on opposite sides of the draft-arms and center-sills, respectively, and, near their ends are apertured to receive the ends of keys 9 that 75 are passed through suitable apertures in the draft-arms and center-sills, cotters 10 or other suitable fastening devices being employed to retain the links 8 in engagement with the keys 9.

To increase the rigidity and strength of the structure we also, as herein shown, preferably employ hollow filler castings 11 and 12, the former of which is interposed between the two draft-arms 7, and the latter 85 between the two center-sills 6, said filler castings at their inner or closed ends abutting against the sides of the bolster. These filler castings are strongly riveted to the draft-arms and center-sills, respectively, as 90 indicated at 13 and 14.

Overlying the body-bolster and inner ends of the draft-arms and center-sills are top and bottom gusset-plates 15 and 16, respectively, these gusset-plates being riveted to the bolster as indicated at 17 and to the upper and lower sides of the filler castings, as indicated at 18.

It will be seen that by reason of the foregoing construction both the draft and buffing 100 strains imparted to the draft-arms 7 are transmitted directly to the longitudinal center-sills 6 through the links 8 and keys 9, thus producing a practically continuous anchorage for the draft and buffing gear from 105 end to end of the car, while at the same time permitting the employment of a continuous bolster, if desired, and avoiding shearing

strains on the rivets by which the top and bottom gusset-plates 15 and 16 are secured to the bolster and to the draft-arms and center-sills.

5 It will be evident to those skilled in the art that the broad principle of the invention is capable of embodiment in other specific forms of connecting devices between the draft-arms and center-sills, and in a companion application filed concurrently herewith, Serial No. 435,809, we have disclosed and claimed another such means of connection. Hence, we do not, in this application, limit ourselves to the particular mechanical embodiment of the connecting means herein disclosed, except to the extent clearly indicated in specific claims.

We claim:

1. In an underframe construction, the combination with a body bolster and draft arms and center sills abutting against opposite sides of said body bolster, of links extending through said body bolster on opposite sides of said draft-arms and center sills, and means connecting the opposite ends of said links to said draft arms and center sills, substantially as described.

2. In an underframe construction, the combination with a body bolster and draft arms and center sills abutting against opposite sides of said body bolster, of links extending through said body bolster on opposite sides of said draft arms and center sills, and keys passed through said draft arms and

center sills and the opposite ends of said links, substantially as described.

3. In an underframe construction, the combination with a body bolster and draft arms and center sills abutting against opposite sides of said body bolster, of filler castings between and riveted to said draft-arms and center-sills, respectively, links extending through said body-bolster on opposite sides of said draft-arms and center-sills, and keys passed through said draft-arms and center-sills and their interposed filler castings, said keys also extending through and connecting said links, substantially as described.

4. In an underframe construction, the combination with a body-bolster and draft-arms and center-sills abutting against opposite sides of said body-bolster, of filler castings between and riveted to said draft-arms and center-sills, respectively, links extending through said body-bolster on opposite sides of said draft-arms and center-sills, keys passed through said draft-arms and center-sills and their interposed filler castings, said keys also extending through and connecting said links, and upper and lower gusset-plates overlying and riveted to said bolster and filler castings, substantially as described.

GEORGE B. ROBBINS.
WILLIAM E. SHARP.
